OF CHICAGO, ILLINOIS, A CORPORATION OF ILLINOIS.

GARAGE OR OTHER BUILDING.

Application filed February 12, 1921. Serial No. 444,562.

To all whom it may concern:

Be it known that we, SAMUEL C. LANCASTER and CHRISTIAN O. HJERMSTAD, citizens of the United States, residing at Port-
5 land, in the county of Multnomah and State of Oregon, have invented a new and useful Garage or Other Building, of which the following is a specification.

In certain types of buildings shown in
10 the prior art for the storage of motor vehicles, there are provided two separate and necessarily independent driveways or traffic areas, one provided for incoming traffic and the other for outgoing traffic. Each of these
15 independent driveways, in order to effect the necessary economy in space, is only of sufficient width to afford clearances for a single line of vehicles and, because they are of opposite pitch, they intersect each other at one
20 point in each turn. Consequently, traffic from one driveway to the other can only be effected at these restricted intersecting points, while at all other parts the driveways must be separated by traffic-blocking
25 curves or partitions, in order to prevent possibility of vehicle wrecking. Adjacent, or flanking, one of the driveways of this structure is a series of tangentially arranged storage stalls which, in order to
30 prevent gravity-discharge of the vehicles, have their floors horizontal and consequently at successive elevations around the helix of the driveway, thereby preventing traffic across and from one storage space to another.
35

It is also apparent that, in order to pass out of the building, each vehicle must be backed out of its stall and then driven forwardly and up the incoming driveway until
40 the next point of intersection of incoming and outgoing driveways is reached, whereupon the vehicle passes, without reversal of driving direction, to the outgoing driveway of opposite pitch.

45 The arrangement above described is both wasteful of available area and is also lacking in efficiency in the matter of time required to handle the vehicles.

The object of our invention is to produce
50 a building so constructed as to facilitate the handling and storage of motor vehicles under conditions which will closely approximate ordinary street-traffic, so that the average driver may drive his car, to and from

its storage space, with safety both to his own car and the cars of others.

The accompanying drawings illustrate our invention.

Fig. 1 is a fragmentary sectional perspective of a building embodying our invention;

Fig. 2 a perspective diagram of one complete turn of the helical floor;

Fig. 3 a plan of a modification; and

Fig. 4 an elevation of Fig. 3.

Considering the application of our invention to the handling and storage of motor vehicles, we call attention to the fact that, from an investment viewpoint, it is desirable that a maximum area within the building be available for storage and a minimum area be devoted solely to traffic, footways, and necessary utilities, such as passenger elevators, etc. On the other hand, from a traffic viewpoint the traffic area should be of such character that incoming and outgoing traffic may be carried on simultaneously without traffic-blocking interference, and that entry to and exit from the storage areas be readily accomplished. It is also highly desirable that the storage area, when unoccupied as such, shall be available as part of the traffic area.

In order to accomplish the desirable results mentioned above, the storage area and traffic area must not only be carefully proportioned, but correlated and be capable of substantially indefinite extension, irrespective of the ground area which may be available for the building.

In the primary form of our invention, we accomplish these results by forming within the enclosing walls 10 of the building, a helical floor 11 which is continuous and uninterrupted from a traffic view point, from bottom to top of the building, the pitch of the helix being sufficient to provide the desired head room and the lateral dimensions being sufficient to provide an easy and safe driving grade, which, preferably, should be low enough to enable the average car and driver to negotiate it at high gear. A certain portion of the floor at the axis of the helix would, of course, be unavailable for vehicle traffic because within the turning radius of vehicles, and this area is utilized, in the present instance, for an elevator 12 and a foot ramp or stairway 13. If part 13 is formed as a ramp, it will, of course, be part

of the helix 11. Immediately adjacent the walls 10 the helix 11 affords storage area for vehicles, indicated by the dotted rectangles 14, and this area is, when not occupied by storage vehicles, available as a traffic area, supplementing the primary traffic area to be described. Between the storage area and the area 13 is an area 15 sufficiently wide to permit two lines of traffic with sufficient clearances, not only between the traffic lines, but also adjacent the stored vehicles and adjacent area 13. Area 13 is preferably separated from traffic area 15 by partition 16 having doorway 17 at desirable points which, it will be understood, may be located at any point. The traffic area 15 is of such character that vehicles may traverse it laterally or diagonally as well as longitudinally, so that vehicles may pass easily into and from the storage area without being confined to the minimum width which would be sufficient to permit longitudinal traffic. By thus correlating and proportioning the storage and traffic areas the width of area 15 may be made much less than would be required if separate and independent incoming and outgoing traffic areas were provided, as in certain structures of the prior art, and consequently, a relatively greater area is available for storage area, and the earning power of the building is thus increased without diminishing the rapidity with which the building may be charged and evacuated. A vacated storage area is also available for traffic, which feature is of very decided importance, especially during the rush hours. It will be readily understood that there will be limited periods during each day when practically all of the traffic will be in one direction or the other. With our construction, the entire width of the traffic and storage area is available to inflowing traffic, the cars being parked in succession in the storage areas, beginning at the top. When the period of maximum outflow arrives, the outflow will begin at the bottom and the vacated storage area will become available as traffic area for the evacuation of the building.

If the floor 11 is a true helix, it is apparent that near two opposite corners of the building, when it is rectangular so as to afford maximum storage area, the vehicles at XX will bear such relation to the grade that they might, under gravity move out from the wall 10 unless their brakes were set. In order to avoid this difficulty, the area 18 at each corner of the building may be distorted from the true helix to a level the radial diagonal of which is on a level with the aligned generatrix of the helix. The connecting storage areas 19 between areas 18 may then be distorted from the helix so as to be laterally horizontal and longitudinally pitched to connect adjacent platforms or spaces 18, connecting throughout their length with the

helix 15 approximately on lines 20, so that the vehicles may readily pass between the traffic and storage areas.

It will, of course, be understood that the particular correlation of traffic and storage areas shown in the drawings is not the only one that can be made with advantage, as that depends somewhat upon the dimensions of ground available for a building. The common traffic areas available for simultaneous double traffic and necessary cross traffic for ingress to and egress from the storage area must, however, flank the storage area.

As indicated at 21, areas will be available for short storage, and at 22 small cars may be stored without seriously impeding traffic. Of course, the corner areas will be more available for comparative dead storage, than for the more live storage which may occupy the freer areas.

The term "helix" is herein used in its broadest sense and not limited to a true helix.

It will become apparent that, in view of the minimum space which is required to provide a double-stream traffic area and a flanking storage area over which traffic may pass, as has been described, the minimum width of floor which can be utilized for the purpose will considerably exceed that which can be formed efficiently in a single span and consequently the intermediate supports for the floor must be so placed as not to materially impede traffic either in the primary traffic area 15 or in the storage area.

We have found that present-day motor vehicles are so averagely proportioned that a floor area of approximately 115 feet square is the minimum for maximum efficiency, and that by placing the intermediate columns 30 in a helical series between the traffic and storage areas, or just within the traffic area, as indicated in Fig. 3, an entirely free and unobstructed primary traffic area 15 is afforded; the columns 30 do not decrease the storage capacity of the storage area; and, being placed substantially an average vehicle-length from the external walls, the space between the walls and columns affords ample traffic width for the free circulation of vehicles and the vehicles may freely circulate between the columns. This is important in order that the storage area, when not occupied, may afford a substantially unobstructed traffic area.

We claim as our invention:

1. A building comprising a multi-turn helical floor forming a helical storage area having a width slightly greater than automobile length and a flanking helical traffic area providing for two lines of longitudinal traffic with freedom for lateral traffic for both lines of traffic at all points throughout its length, and a helical series of separated columns interposed between successive turns

of the helix between the traffic area and storage area and so as not to prevent traffic over the storage area between the columns and between the columns and the walls.

5 2. A building comprising a multi-turn helical floor forming a helical storage area having a width slightly greater than automobile length, along which traffic may flow when not used for storage, and a flanking 35
10 helical traffic area providing for two lines of longitudinal traffic with freedom for lateral traffic for both lines of traffic at all points throughout its length, and a helical series of separated columns interposed between successive turns of the helix between the traffic area and storage area and so as not to prevent traffic over the storage area and between the columns.

5 3. A building having corner areas and 20 comprising a multi-turn helical floor forming a helical storage area and a flanking helical traffic area providing for two lines of longitudinal traffic with freedom for lateral traffic, the storage area being distorted from 25 but merging into the traffic area, to form a helical series of substantially level areas at the corners of the building and substantially laterally-level ramps connecting the corner areas.

30 4. A building comprising a multi-turn

helical floor, the successive turns of said helix being supported by a series of separated columns so arranged as to provide a storage area unobstructed to traffic and to provide two traffic paths unobstructed to traffic, said traffic paths and storage area merging and being unobstructed to traffic to permit of a free lateral traffic across said longitudinal traffic paths and into the storage area.

5 5. A building comprising a multi-turn helical floor, said helical floor being unobstructed to traffic throughout its entire length both laterally and longitudinally, said helical floor thereby having formed throughout its length a helical storage area and a flanking 40 helical traffic area providing for two lines of longitudinal traffic with freedom for lateral traffic throughout its length.

6. A building comprising a multi-turn, helical floor forming a conjoint traffic and 50 storage area and providing two undivided traffic paths, said traffic paths and conjoint traffic and storage area merging to permit of free lateral traffic across said traffic paths and into said conjoint traffic and storage area.

In witness whereof we have hereunto set our hands at Chicago, Illinois.

SAMUEL C. LANCASTER.

CHRISTIAN O. HJERMSTAD.
